UNITED STATES PATENT OFFICE.

HENRY C. WATERS, OF BOSTON, MASSACHUSETTS.

RULER.

1,255,251.

Specification of Letters Patent.

Patented Feb. 5, 1918.

Application filed January 2, 1917. Serial No. 140,026.

To all whom it may concern:

Be it known that I, HENRY C. WATERS, a citizen of the United States, residing at Boston, in the county of Suffolk and State 5 of Massachusetts, have invented new and useful Improvements in Rulers, of which the following is a specification.

My invention is an improved flexible ruler, especially adapted for use upon curved surfaces, and consists in certain details of construction, by which it is rendered very convenient in operation and accurate in placing the ruled lines.

In the drawings, Figure 1 shows an upper, 15 top or plan view of my improved ruler;

Fig. 2 shows a view of the underside;

Fig. 3 is a front edge view of the device;

Fig. 4 is a perspective view; and

Fig. 5 is a longitudinal section on line 20 5-5 of Fig. 1, looking in the direction of the arrows.

It is obvious in ruling in the large account books in common use today, the curvature of the leaf toward the binding edge, at the 25 center of the book, renders it difficult to use the ordinary stiff ruler, which is practically inflexible and has to be rocked upon the curved surface as the line is drawn over that part of the page. To meet this difficulty 30 flexible rulers have in the past been invented, capable of being flexed by pressure, into conformity with the surface to be ruled, but so far as I know no ruler has heretofore been known having this flexible capacity which 35 could in fact be flexed by the user in operation.

My improved ruler is made up of two sheets, *a*, *b*, of hard, flexible and resilient material, preferably thin sheet spring brass, 40 which are spaced apart to a suitable distance by several sheets of flexible material, *c*, such for example as blotting paper. The strips, *a*, *b*, are connected together by a slot and pin connection by means of pins, *d*, *d*', 45 which are secured to the under strip *b* and pass through slots *c*' in the paper strips and enter slots *a*' in the upper strip *a*, heads, *d*', retaining the engagement while permitting longitudinal movement of the parts with 50 reference to one another.

The upper strip, *a*, is wider than the strips, *b*, *c*, and projects to provide a ruling straight edge. The upper strip *a* is also larger than the other strips, along its ruling 55 edge, forming ears, *e*, projecting at either end.

To the middle of the strip, *a*, on its upper surface, is secured a rearwardly projecting flat handle *E*, of thin metal, similar to that of which the strip, *a*, is formed, and suitably shaped to fit the palm of the hand, leaving the fingers free.

In its best form, as illustrated in the drawings, the strips *a*, *b*, are permanently set to a slight regular and symmetrical curve. 60 In operation, the curve required is rarely symmetrical, as for example, upon approach to the bound edge of an account book leaf, one end of the ruled line and ruler will be upon a practically plane surface, while as 65 the bound edge of the leaf is approached, the leaf begins a rapid curve. With my device, the ruler is manipulated and held in proper position by means of the handle *E*, which is received firmly in the palm of the 70 hand, the fingers being free to be spread and severally press upon the ruler at several points in the length of the ruler, thus forcing close conformity throughout the length 75 of the ruler.

My improved ruler is especially useful in 80 ruling upon curved surfaces, the freedom of the fingers making it possible to press the ruler into close conformity with any curve, so that the entire under surface is in frictional engagement with the page, causing 85 the ruler to maintain its adjusted position firmly, while the ruling proceeds. A slight release of pressure causes the ruler to resume its normal curve, resting on the page merely 90 at its ends, so that it can be slid about the page with ease. With my ruler, ruling at 95 the foot of the page is as easy as at any other point. The fingers are not cramped in operating it and placing and adjusting can 100 be accomplished in much less time than usual and held in accurate placement with minimum pressure or exertion. In modern systems of accounting loose leaf ledgers are 105 commonly employed and in these the leaves are ruled only from top to bottom for figures, the entries being typewritten without any crosswise ruling. In ruling upon such sheets it is desirable that a ruled line should be properly ended at the appropriate longitudinal line, and the ears *e*, and square edges *e*' provide for this. The edge *e*' which is 110 perpendicular to the ruling edge *a*'', is aligned with the longitudinal ruling, the ear *e* crossing the same and in this way the ruled line can be brought accurately up to the longitudinal line.

In operation the handle E is placed well up in the palm of the hand, one edge in contact with the ball of the thumb, the fingers spread and engaging the ruler, a, at 5 three or four points along its length, to force it into accurate conformity with the particular curve of the particular page and into frictional engagement throughout its length. The ruling edge, a'', is well above and in 10 advance of the other parts of the ruler and when the ruling is complete a release of pressure permits the ruler to lift itself perpendicularly from the page, thus avoiding any possibility of smearing the page should the 15 ruling edge by accident have been fouled by ink.

I claim:—

1. A flexible ruler, provided with an offset handle having thin edged sides, projecting from the side of the ruler opposite to the ruling edge and adapted to be grasped by the thumb and the palm of the hand. 20
2. A flexible curved ruler, provided with an offset handle projecting from the side of the ruler opposite to the ruling edge and 25 adapted to be grasped by the palm of the hand, leaving the fingers free to press upon the rulers.

Signed by me at Boston, Massachusetts, this 28th day of December, 1916.

HENRY C. WATERS.
